(57) **CLAIM**

The ornamental design for a lighted dishwasher door, as shown and described.

DESCRIPTION

FIG. 1 is a front perspective view, from the top, of a lighted dishwasher door showing our new ornamental design;

FIG. 2 is a front view thereof;

FIG. 3 is a top view thereof;

FIG. 4 is a cross sectional view of the door shown in FIG. 1; and,

FIG. 5 is an enlarged view of the detail shown in FIG. 4. The broken lines of the lighted dishwasher door show surrounding structure or environment and do not form part of the claimed design. The radiating broken lines in FIGS. 4 and 5 represent one or more light beams and form no part of the claimed design.

The rear of the dishwasher door, and the bottom, sides, rear and/or top of the dishwasher are unornamented or simply not claimed and form no part of the claimed design.
